UNITED STATES PATENT OFFICE.

SAMUEL RIVELIS, OF PHILADELPHIA, PENNSYLVANIA.

FASTENING DEVICE FOR WEARING APPAREL.

Application filed October 18, 1921. Serial No. 508,574.

To all whom it may concern:

Be it known that I, SAMUEL RIVELIS, a citizen of the United States, residing at Philadelphia, county of Philadelphia, and 5 State of Pennsylvania, have invented certain new and useful Improvements in Fastening Devices for Wearing Apparel, of which the following is a specification, reference being had to the accompanying drawings.

My invention relates generally to fastening devices for securing wearing apparel, and more especially to fasteners useful in connection with ladies' foot wear.

15 Ladies' low shoes or pumps, of the type in vogue at the present time, are held to the foot by straps which extend across the instep. These straps are ordinarily permanently fastened to one side of the pumps 20 while their free ends are detachably secured to the other side. The paramount object of my invention is to provide, for the purpose last mentioned, a simple and efficient means capable of being easily attached, readily manipulated in securing and detaching the instep strap, and which after being secured, will not yield readily to being accidentally disengaged.

I also aim to enhance the utility of fasteners, of the special type referred to, by provision, for use in association therewith, of ornamentation capable of being readily interchanged in accordance with the taste of the wearer.

35 Other objects and attendant advantages will become readily apparent from the detailed description of the two typical forms of my invention which follows.

In the drawings, Fig. I is a perspective view of a lady's low shoe or pump showing the manner of use of a fastening device conveniently embodying my invention in one form.

Fig. II is a detail sectional view on a 45 larger scale showing the two members of the fastening device in engaged relation.

Fig. III is a perspective view of one of the members of the device in the form of a headed stud.

50 Fig. IV is a similar view of the complementary engaging member of the fastener; and

Fig. V is a perspective view of a modified form of the complementary engaging 55 member of the fastener.

Referring first to the embodiment illus-

trated in Figs. I to IV inclusive, it will be observed that a fastening device of my invention comprises a headed member in the form of a stud 1 adapted, in the present instance, to be secured in the end of the instep strap S of the low shoe or pump P, and an engaging member 10 adapted to be secured to the flap F at one side of the pump.

At a slight distance behind its head 2, 60 the stud 1 has an integral collar 3 and its shank is threaded as at 4 for the attachment of interchangeable ornamental buttons such as shown at 5. In applying the member 1, its shank is thrust through the strap S 65 near the free end of the latter and the button 5 thereafter screwed onto the protruding portion of said shank with the result that the material of the strap is engaged between the collar 3 and the button. 70

The companion engaging member 10 of the fastening device is, in this embodiment, shown as being rectangular in form and made as a sheet metal stamping with a raised central portion 11 which is flanked 80 at opposite sides by comparatively narrow flanges 12, 12. Said flanges are apertured as at 13, 13 so that the member 10 may be readily secured to the flap of the pump by sewing or otherwise.

85 The raised portion 11 of the member 10 has a slot 15 whose mouth is flared as clearly shown in Fig. IV, and which serves as an approach to a terminal notch 16. In securing the strap, the head 2 of the member 1 is inserted within the raised portion 11 of the member 10. Incidentally, the portion of the shank between the head 2 and collar 3 of the member 1 is advanced through the slot 15 (this being facilitated 90 by virtue of the flaring of the slot) and forced past the restriction at 17 and into the notch 16 and thus yieldingly retained in the latter.

95 Referring now to the modification of Fig. V, the complementary member there shown has an embossed or raised body portion 20 which is pierced by an opening comprising a lobe 21 of a diameter sufficiently large to readily admit the head 2 of the element 1, and a notch 22, for engaging the shank 100 of the latter member, which is communicative with the aforesaid lobe through a restricted slot or passage 23. The modified engagement member differs further from the 105 previously described form in that it has integral depending prongs 24, 24 which are 110

adapted to be turned over toward each other after penetrating the material whereto the member is to be fastened.

While I have shown and described my invention as especially applicable to shoes, it is obvious that it may be employed with equal advantages for other purposes as well.

Having thus described my invention, I claim:

10. A fastening device comprising a threaded shank having a flange at one end, an ornamental button applied to the shank to grip a member to be secured between the button and flange, a head on the shank spaced from the flange, and a complementary mem-
- 15

ber including spaced flanges to grip the shank between the head and flange and adapted to receive the parts at one end of the flanges in tight engagement, with means forming part of the complementary member for attachment to another member to be secured.

In testimony whereof, I have hereunto signed my name at Philadelphia, Pennsylvania, this third day of October, 1921.

SAMUEL RIVELIS.
